Inventor

DES. 2197

J. L. Secat, of New Haven, Conn't

Assignor, to

Treat, Linsey, & Co, of the same place.

Letters Patent No. 2197, Dated Oct. 10-1865.

Design for a Reed Organ Case.

The schedule referred to in these Letters Patent and making part of the same.

To all whom it may concern:

Be it known that J. L. Treat, of New Haven, in the County of New Haven, and State of Connecticut, have originated a new design for Reed Organ Cases, and do hereby

by declare the following, after taking a connection with the accompanying drawings and the letters of reference marked theron, to be a full, clear and exact description of the, and which said drawings constitute part of this specification, and represent a perspective view of my new design for Reed Organ Case.

The design which I wish to secure by Letters Patent relates to cases for Reed Organ or similar instruments, and consists in the peculiar finish of the top of the plinth and the panel base.

A is the top, B the plinth, and C the panel base, the edge of each finished in a serpentine form as seen in figs. 1 and 2. This edge is of slightly convex section as seen in figs. 2 and 3. This edge is wrought upon the several parts and forms a new neat and tasteful design.

I claim as my production and desire to secure by Letters Patent, the design for an organ case &c, as shown and described.

Witness,

John E. Earle,

Rufus H. Sanford,

J. L. Treat,
